UNITED STATES PATENT OFFICE.

RICHARD HARRISON MARTIN, OF GAINESVILLE, GEORGIA, ASSIGNOR OF ONE-FOURTH
TO GEORGE H. PURVIS, OF GAINESVILLE, GEORGIA.

PACKET-HOLDER.

1,334,624.

Specification of Letters Patent. Patented Mar. 23, 1920.

Application filed September 8, 1919. Serial No. 322,271.

To all whom it may concern:

Be it known that I, RICHARD H. MARTIN, a citizen of the United States, residing at Gainesville, in the county of Hall and State 5 of Georgia, have invented a new and useful Packet-Holder, of which the following is a specification.

This invention has reference to flexible securing devices, and more particularly to devices employed for retaining a plurality of 10 letters or similar articles together, to facilitate the handling of the same, in transit.

The primary object of the invention is to provide a clip or securing means for securing 15 the ends of a cord or other flexible elements against displacement on the pack or bundles of letters associated therewith.

A further object of the invention is to provide a metallic clip having clamping 20 jaws for clamping the flexible binding element thereto, to facilitate the quick and easy attachment of the binding element to the pack.

A still further object of the invention is 25 to provide a clip of this character which is punched from a single sheet of metal, the tongues and jaws forming part thereof, being formed integral therewith.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed, may be made within the scope of what is claimed without departing from the spirit of the invention.

Referring to the drawing:—

40 Figure 1 illustrates a top plan view of a pack of letters, or cards, with my invention applied thereto, showing the manner of positioning the flexible securing element thereto.

45 Fig. 2 illustrates a top plan view of the clip, forming an important feature of the present invention.

Fig. 3 illustrates an enlarged sectional view taken on line 3—3 of Fig. 2, and

50 Fig. 4 illustrates an end view in elevation of the same.

Referring to the drawing in detail, the reference character 5 designates one of the jaws of the clip, the same being formed of 55 a continuous strip of metal having flexible

qualities, and includes an opposed jaw 6, forming a part of the jaw 5 and a curved portion 7, formed between the jaws 5 and 6, the same being provided with an opening 8 through which extends one end of the flexible securing element 14, which end, is provided with a knotted portion for contacting with the inner edges of the connection between the jaws 5 and 6 adjacent the opening 8, for preventing movement of the flexible 65 securing element, in one direction, with relation to the clip.

The jaw 6, is provided with a cut-out portion 9, which provides a curved tongue 10, of a length to extend upwardly through the 70 opening 11, formed in the opposite jaw 5, for purposes to be hereinafter more fully described.

As shown, the tongue 10, is curved toward the forward ends of the jaws 5 and 6, the 75 curved portion lying in a plane above the upper side face of the jaw 5, the extreme end 12 thereof, extending downwardly and terminating at a point in the same plane with the lower wall of the jaw 5.

This jaw 5, is curved downwardly, intermediate its length, as at 13, to provide camming surfaces, over which the flexible element 14 may pass, thereby guiding the flexible element 14, to its proper locked position, 85 under the tongue 10, thus facilitating the applying of the device to a letter pack.

It will thus be seen that after the flexible member 14, has been properly positioned adjacent the curved member, or tongue 10, the 90 jaw 5, is depressed which permits the flexible element to engage under the tongue 10, whereupon the flexible element is tightly gripped between the jaw 5, and under surface of tongue 10, when the jaw 5 has been 95 released, and the same assumes a position as indicated by Fig. 3 of the drawing.

While I have disclosed, in Fig. 1 of the drawing, the preferred manner in passing the flexible element 14 around the pack, it 100 is to be understood that the manner of applying the flexible element, may be varied to meet the requirements or changes necessary, in applying the flexible member to packs of various shapes and sizes.

Having thus described the invention what is claimed is:—

In a package tie, a clasp including opposed jaws, one of said jaws having a tongue formed integral therewith, said 110

tongue extending upwardly and being curved and having its free end formed into a hook, the end thereof lying below the lower edge of the opposed jaw, the opposite 5 jaw having a relatively long cut out portion, the cut out portion being of a length to provide a space between the forward portion of the tongue and one wall of the slot, and a 10 space between the rear portion of the tongue and one wall of the slot to permit one jaw to

be moved with relation to the other, and said tongue normally lying within the confines of the cut out portion.

In testimony that I claim the foregoing as my own, I have hereto affixed my signature in the presence of two witnesses. 15

RICHARD HARRISON MARTIN.
